CAR ROOF

John J. Tatum, Baltimore, Md.

Application February 24, 1934, Serial No. 712,833

3 Claims. (CL. 108—5)

This invention relates to improvements in roofs for railway cars of the box or house type.

One object of the invention is to provide a novel construction of running board which stiffens and gives greater strength and rigidity to the roof and ensures greater safety to trainmen against being thrown from the roof.

Another object of the invention is to provide a Mansard style of roof giving greater inside vertical height, or free inside height, and embodying the novel construction of running board.

The invention consists of the features of construction, combination and arrangement of parts, hereinafter fully described and claimed, reference being had to the accompanying drawing, in which:

Fig. 1 is a transverse section through the roof portion of a car embodying my invention.

Fig. 2 is a fragmentary top plan view of the same.

Figs. 3 and 4 are similar views showing a modification in the running board structure.

Referring now more particularly to Figs. 1 and 2 of the drawing, 1 represents the upper portion of a car body of box or house type having side walls formed of the outer side sheets 2 and the lining 3 of any suitable material, the side sheets and lining being joined at their upper edges or at the eaves line by Z-shaped eaves or side plates 4, to which the upper edges of the side sheets may be riveted or otherwise suitably secured, as indicated at 5. Upon these plates or beams 4, and upon corresponding or other suitably constructed plates or beams upon the car end walls, is supported a roof 6. This roof is shown as being of maximum height at a central point or ridge 7 and formed of sheets 8 and 9 sloping at a suitable angle, transversely of the car, downwardly and outwardly toward the side sheets, said roof sheets 8 and 9 terminating at their outer edges in flanges 10 bent downwardly at a sharp angle therefrom.

As shown in the present instance, the roof proper 6, which is of suitably less width than the width of the car, or the distance between the side walls or sheets, but which extends transversely the major portion of the distance between the roof center and side sheets, is supported at a proper elevation above the eaves plates or beams 4 so as to form a storage space or chamber 11 located in the roof zone or above the level of said eaves plates or beams. To this end, extension sheets or hip sheets 12 are provided at the sides of the roof which are of relatively less transverse extent than the roof sheets

to form a supporting roof base, and which may be sloped or pitched at a greater angle than the roof sheets, whereby the roof 6 is carried upon the side and end walls at such height as to provide a storage space or chamber 11 of the desired depth. These sheets 12 extend upwardly and inwardly at the desired angle of inclination or slope from the upper flanges of the side or eaves plates or beams 4 to the side of the roof and are provided at their lower edges with flanges 13 suitably secured, as by rivets 14, to the upstanding flanges of the plates or beams 4 and provided at their upper edges with flanges 15 suitably secured, as by rivets 15', to the downturned flanges 10 of the roof sheets 8 and 9. 15

By this construction a roof is provided which is elevated for the purpose of making the car as high as possible between the floor and ceiling without encroaching on the American Railway Association clearance lines, and in which the roof 20 is stably supported by the inclined extension or hip sheets 12 which properly restrict the width of the roof and at the same time are so sloped as to form with the sloping roof sheets a proper water shed for the purpose of carrying off all 25 rain water or water from melting ice or snow without the necessity of employing special means for this purpose or protecting parts of the side roof structure against leakage or conditions causing rust. The storage space 11 thus afforded in 30 the roof zone and above the level of the side sheets is of considerable depth and substantially equal in width to the storage space in the car body below and of sufficient cubic capacity in practice to receive loading devices or racks 35 of various kinds for supporting automobiles or other elevated lading in the upper portion of the car, and which may be stored or used for supporting and storing lading arranged above the level of other lading carried in the car body below. As a result, the full height or depth of the body will be left clear to be filled with freight or lading which may extend up into the roof storage chamber 11, thus greatly increasing the cubic carrying capacity of the car, or the car 45 body may be filled with freight or lading up to its full height and the chamber 11 employed to receive automobile loading frames or racks which may be stored therein when the car is not being used for the transportation of automobiles, thus 50 allowing one and the same car to be employed for the transportation of automobiles as well as other kinds of freight. In the use of automobile frames or racks for carrying automobiles in the upper portion of a box or house car, which are 55

foldable or movable to a storage position up against the roof, my improved construction permits of the reception of such frames or racks within a chamber 11 which is wholly in the roof 5 zone, and above the level of the eaves line represented by the plates or beams 4, thereby allowing such frames or racks to be carried without the same extending downwardly into and limiting the lading receiving space of the body proper, 10 as is the case in the use of such frames or racks in box or house cars of ordinary construction.

I provide at the center of the roof a running board or raceway platform structure which stiffens and strengthens the roof while at the same 15 time forming a runway for the movements of trainmen which ensures maximum safety to the trainmen under all running conditions and in all kinds of weather. To this end I provide the roof with a central, longitudinally extending upstanding boss or platform base 16 formed by stamping or upsetting the metal in an upward direction, which base forms a support for a running board proper. As shown, this base is formed by projecting portions of the sheets 8 and 9 upwardly 20 in the form of flanges or risers 17 which are connected by a horizontal platform portion 18 and forming a narrowed base for the running board 19. This running board is preferably formed of heavy sheet metal extending from end to end 25 of the roof and which is preferably of a greater width than the width of its platform base, so that the longitudinal edges of the platform project beyond the flanges 17 and form grip flanges or extensions 20 which afford continuous grips 30 or handholes which a trainman may grasp, in cases of emergency, to give him a secure hold to prevent him from being thrown off the car, the construction being such that the trainman may either sit or lie down on the roof or running board and hold firmly onto the grip flanges. 35 The running board may be stamped or otherwise formed or finished to provide thereon roughened surfaces, so as to adapt it to serve as an anti-skid or anti-slipping running board. The running board may be secured to the base 18 by 40 welding or riveting, fastening rivets 21 being shown as employed in the present instance. Also, if desired, the flanges 20 may be provided with down-bent portions 20', thus forming angular 45 flanges affording non-slipping grips.

In Figs. 3 and 4 of the drawing I have shown a modified construction in which the platform supporting base 16', instead of being in the form of a longitudinally continuous boss, comprises spaced transverse bosses supporting a runway 5 plate of the construction previously described and which may be secured to the bosses in the same manner.

From the foregoing description, taken in connection with the drawing, the construction of 10 my improved car roof will be readily understood, and it will be seen that the invention provides a roof of the type described giving maximum interior vertical height, or free inside height, for storage purposes, and which embodies a running 15 board of novel structure giving greater strength and stiffness to the roof and gripping means affording greater security to trainmen against being thrown from the train. Other advantages of the invention will be fully understood by those versed 20 in the art without a further and extended description.

While the features of construction herein disclosed for purposes of exemplification are preferred, it will, of course, be understood that 25 changes in the form, construction, arrangement and proportions of parts within the scope of the appended claims may be made without departing from the spirit or sacrificing any of the advantages of the invention. 30

What I claim is:—

1. In a car roof construction, a car having side sheets, sloping roof sheets provided at the peak with a running board base pressed upward therefrom, and a running board sheet fastened to said 35 base and extended at its side edges beyond the base to form grip flanges.

2. In a car roof construction, a roof comprising metal sheets having a bossed up portion forming a runway supporting base, and a runway plat- 40 form, wider than the base, resting and secured to said base.

3. In a car roof construction, a roof comprising metal sheets having a bossed up portion forming a runway supporting base, and a sheet metal run- 45 way platform resting on and secured to said base, said platform being of greater width than the base whereby its longitudinal side edges provide extending grip flanges at opposite sides of the base.

JOHN J. TATUM. 50
